DESIGN FOR A COMBINED BATTERY VENT PLUG AND HYDROMETER

George C. Appel, Milwaukee, Wis., assignor to
Globe-Union Inc., Milwaukee, Wis., a corpora-
tion of Delaware

Application April 22, 1946, Serial No. 128,825

Term of patent 14 years

(Cl. D52—7)

To all whom it may concern:

Be it known that I, George C. Appel, a citizen of the United States, residing at Milwaukee, in the county of Milwaukee and State of Wisconsin, have invented a new, original, and ornamental Design for Combined Battery Vent Plug and Hydrometer, of which the following is a specification, reference being had to the accompanying drawing, forming a part thereof, and in which:

Figure 1 is a vertical, elevational view of a combined battery vent plug and hydrometer, showing my new design; and

Figure 2 is a bottom plan view.

I claim:

The ornamental design for a combined bat-
tery vent plug and hydrometer, as shown.

GEORGE C. APPEL.
